ATTORNEY

UNITED STATES PATENT OFFICE.

HORACE T. THOMAS, OF LANSING, MICHIGAN.

STARTER FOR INTERNAL-COMBUSTION ENGINES.

1,224,042.

Specification of Letters Patent. Patented Apr. 24, 1917.

Application filed December 9, 1915. Serial No. 65,997.

To all whom it may concern:

Be it known that I, HORACE T. THOMAS, a citizen of the United States, residing at Lansing, county of Ingham, State of Michigan, have invented a certain new and useful Improvement in Starters for Internal-Combustion Engines, and declare the following to be a full, clear, and exact description of the same, such as will enable others skilled in the art to which it pertains to make and use the same, reference being had to the accompanying drawings, which form a part of this specification.

My invention relates to starters for internal combustion engines and an object of my improvements is to provide a starter especially adapted to use upon an automobile.

I accomplish this object in the device illustrated in the accompanying drawings in which,

Figure 1 is a side elevation of an apparatus embodying my invention with so much of an automobile as is necessary to illustrate its connection therewith.

Fig. 2 is a sectional detail elevation, the section being approximately on the line B—B Fig. 1.

Fig. 3 is a side elevation of the operating ring partly in section.

Fig. 4 is an edge elevation of the same.

Fig. 5 is a detail sectional elevation on the line E—E Fig. 1.

a represents the floor of an automobile. a² is a supporting frame work secured to the chassis a³ a³. c is a socket, or sliding bearing piece, extending upward from the frame a² through the floor a.

b is a rod fitting and adapted to slide in the socket c. d is the engine shaft. e is a ratchet wheel secured to the shaft d. f is a sprocket wheel mounted concentric with the shaft d and adapted to rotate around said shaft.

i is an electric motor for furnishing power for starting the engine. h is the operative shaft of the motor i. g is a sprocket wheel upon the shaft h. j is a sprocket chain extending over and engaging the wheels f g.

k is a rock lever pivoted at k² and having arms k³ and k⁴ extending therefrom. The lower end of the rod b rests upon the outer end of the rock lever k and when the rod b is pressed downward said rock lever is oscillated. c² is a set-screw by which the travel of the rock lever k is limited. t is a

rod or plunger pivoted to the outer end of the arm k³ and extending vertically downward. w² is a coil spring acting to press the rod t downward and to hold the lever k in its normal position. v is a set screw extending upward from the outer end of an offset from the rod t. q is a vertically reciprocating rod bearing the contact plates r (Fig. 5) on its upper end, which at the upper end of the travel of the rod q, make contact between the binding posts s s and complete the circuit through the motor i setting said motor in operation. The screw v contacts the lower end of the rod q and presses said rod upward setting the motor in operation, as above described when the rock lever k is oscillated.

n is a ring sleeved and adapted to turn a limited distance upon the hub of the wheel f (Fig. 2). This ring is provided with a V-shaped groove n². o is a pawl adapted to engage in the teeth of the ratchet wheel e. The pawl o is secured upon a shaft o² (Fig. 2) pivoted in the web of the sprocket wheel f and extending through said web at right angles to the plane of the wheel. p is a spring upon the wheel f acting to hold the pawl yieldingly in its disengaged position. n³ is a socket in the ring n. o³ (Figs. 2 and 3) is an arm extending at right angles from the shaft o² at the opposite end of said shaft to that at which the pawl o is located. The rod o³ engages at its end remote from the shaft o² in the slot n³.

m is a cylindrical brake band engaging in the groove n² of the operating ring n. m² is an eye bolt adjustably secured by the usual nuts to the frame a². One end of the brake band m engages through the eye of the bolt m². m¹ is a spring connecting the outer end of the arm k⁴ with the end of the brake band m remote from that which is secured to the eye bolt m².

The operation of the above described device is as follows:

When it is desired to start the engine the rod b is depressed oscillating the lever k and completing the circuit through the motor i, which sets said motor in operation rotating the sprocket wheel g and thereby rotating the sprocket wheel f by means of the chain j.

The sprocket wheel f will turn freely carrying the operating ring n with it until the lever k is sufficiently depressed to put a tension upon the brake band m and thus re-

tard the motion of the operating ring n^1 which will act through the wall of the slot n^3 to oscillate the shaft o^2 and carry the pawl o into engagement with a tooth of the 5 wheel e . This will unite the wheel f with the shaft of the engine and further motion of the motor i will rotate said shaft and set the engine in motion in the usual way.

When the engine starts up it is free to 10 run ahead of the motor and should there be a reverse action of the engine the connections may yield by overcoming the friction of the belt m , thus avoiding undesirable effects from such reverse action. The spring 15 n^4 will permit of a loosening of the brake band in case of any reverse movement of the ring n .

What I claim is:

1. In a starter, the combination of a motor 20 and engine shafts normally disconnected, transmission means between the motor and engine shafts including normally disconnected parts, frictional means coöperative with one of the parts to connect the parts 25 and means under the direct control of the operator for rendering the frictional means operative.
2. In a starter, the combination of a motor 30 and engine shafts normally disconnected, transmission means between the motor and engine shafts including normally disconnected parts, frictional means coöperative with one of the parts to connect the parts, and means under the direct control of the 35 operator for setting said motor in operation

adapted to cause the action of said frictional means for the purpose described.

3. In an apparatus of the kind described, an engine shaft, a ratchet wheel upon said shaft, a wheel adapted to be actuated by the starting motor and to rotate free of said shaft, a pawl upon said wheel adapted to move into engagement with the teeth of said ratchet wheel, a friction operated part 40 engaging said pawl eccentrically, and means 45 for frictionally actuating the said part.

4. In an apparatus of the kind described, an engine shaft, a ratchet wheel upon said shaft, a wheel adapted to be actuated by the starting motor and to rotate free of said 50 shaft, a ring concentric and adjacent to said wheel, a pawl upon said wheel adapted to move into engagement with the teeth of said ratchet wheel, said ring engaging said pawl 55 eccentrically, and means for applying frictional resistance to said ring.

5. In an apparatus of the kind described, an engine shaft, a ratchet wheel upon said shaft, a wheel adapted to be actuated by the starting motor and to rotate free of said 60 shaft, a ring concentric and adjacent to said wheel, a pawl upon said wheel adapted to move into engagement with the teeth of said ratchet wheel, said ring engaging said 65 pawl eccentrically, a yielding means for applying frictional resistance to said ring.

In testimony whereof, I sign this specification.

HORACE T. THOMAS.
